UNITED STATES PATENT OFFICE.

JOSEPH H. FLETCHER, OF PORTLAND, OREGON.

GAUNTLET-GLOVE.

No. 928,256.

Specification of Letters Patent.

Patented June 1, 1909.

Application filed January 8, 1909. Serial No. 471,348.

To all whom it may concern:

Be it known that I, JOSEPH H. FLETCHER, a citizen of the United States, residing at Portland, in the county of Multnomah and 5 State of Oregon, have invented a new and useful Gauntlet-Glove, of which the following is a specification.

This invention relates to a gauntlet glove in which the glove and the gauntlet are separable, in order that the gauntlet may be saved when the glove is worn out, and the object of the present invention is to provide an improved fastening for connecting said parts, and also to provide means for fitting 15 the gauntlet to the wrist, so that the entrance of cold air, etc., is effectually prevented.

With the foregoing objects in view, the invention consists in a novel construction 20 and arrangement of parts, to be hereinafter described and claimed, reference being had to the drawing hereto annexed, in which:—

Figure 1 is a perspective view of the invention, partly broken away. Fig. 2 is a transverse section through the connection between the two parts, on substantially the line 2—2 of Fig. 1. Fig. 3 is a transverse section on the line 3—3 of Fig. 2.

In the drawing 5 denotes a glove of the ordinary kind, and 6 is the gauntlet, to which the glove is to be detachably connected. The wrist portion of the gauntlet is provided with a gusset 7 of flexible material, so that said portion of the gauntlet 35 may be drawn together to encircle the wrist sufficiently tight to exclude cold air, etc. The gauntlet is made of stiff leather or other material suitable for this purpose, and the gusset is a strip of soft leather or other 40 material of the required flexibility, in order that it may be drawn together, to fit the gauntlet around the wrist, as stated.

On one side of the gusset the gauntlet is provided with a short strap 8, carrying one 45 of the members 9 of a stud and socket, or other form of separable fastening, the other member 10 of said fastening being secured to the gauntlet on the other side of the gusset. The strap is adapted to be extended 50 across the gusset, and secured by the fastening, whereby the gusset is drawn together,

and the gauntlet properly fitted around the wrist.

The gusset is formed by making a substantially V-shaped notch in the edge of the 55 wrist portion of the gauntlet, and sewing or otherwise securing to the gauntlet on the inside thereof, to extend across the notch, the flexible strip of leather or other material heretofore described.

The strap 8 may be formed integral with the gauntlet as shown.

To the inside of the wrist portion of the gauntlet is sewed or otherwise secured a band 11, formed with button-holes 12. This 65 band extends entirely around the inside of the gauntlet, up to the gusset, and the latter is also provided with button-holes 13. The band is preferably made in two pieces, as shown in Fig. 2, in order that it may be more 70 easily attached to the gauntlet, the pieces meeting at one end at the seam of the gauntlet, so that said pieces may be sewn to the latter before it is completed. To the outside of the glove 5, at the edge of the 75 wrist portion thereof, are sewed or otherwise secured buttons 14, which are engageable with the button-holes 12 and 13, whereby the gauntlet and glove are detachably connected. This edge of the glove is also reinforced by strips 15, sewed or otherwise secured thereto.

It will be seen, from the foregoing, that I have provided means whereby the gauntlet and the glove may be quickly and easily connected or separated, and there is no danger of said parts becoming separated by the movement of the wrist. By the gusset 7 and the strap 8, the wrist portion of the gauntlet and glove may be drawn tightly 80 together to exclude air, etc., and the parts will fit the wrist as comfortably as an ordinary glove. In use, the glove and the gauntlet will be put on together as though 85 they were formed in one piece.

What is claimed is:—

A gauntlet glove comprising separable gauntlet and glove sections, the wrist portion of the gauntlet being provided with a gusset having buttonholes, a strap detachably connected across the gusset, a band secured on the inside of the wrist portion of 95 100

the gauntlet and extending entirely around the same up to the gusset, and provided with buttonholes, said band being in two sections which meet at the seam of the gauntlet, and 5 buttons secured to the wrist portion of the glove on the outside thereof, said buttons being engageable with the aforesaid buttonholes of the band and the gusset.

In testimony that I claim the foregoing as my own, I have hereto affixed my signature 10 in the presence of two witnesses.

JOSEPH H. FLETCHER.
